Patented Dec. 19, 1922.

UNITED STATES PATENT OFFICE.

RICHARD D. GALLAGHER, OF CHICAGO, ILLINOIS, ASSIGNOR TO ROOS FOUNDRIES, INC., OF CHICAGO, ILLINOIS, A CORPORATION OF ILLINOIS.

DERAIL.

Application filed March 2, 1922. Serial No. 540,405.

To all whom it may concern:

Be it known that I, RICHARD D. GALLAGHER, a citizen of the United States, residing at Chicago, in the county of Cook and State of Illinois, have invented certain new and useful Improvements in Derails, of which the following is a specification.

My invention relates to derails, and particularly to a portable derail which is self-locking and which is designed to protect re-pairmen working on cars on the line tracks, as well as to serve as a temporary signal under unusual circumstances.

An object of the invention is to provide a derail which may be readily portable, self-contained, and which may be quickly and securely fastened to a track rail.

Another object of the invention is to provide a derail which may be temporarily and quickly applied to a track rail and locked thereon.

A further object of the invention is to provide a portable derail which may be quickly secured in position by cam action.

A further object of the invention is to provide a portable derail having a cam for locking the same in position and a target signal associated with said cam, which serves as a handle for actuating the same as well as a temporary danger signal.

A still further object of the invention is to provide a portable derail adapted to be secured in position by a clamping action and a member projecting in the path of a car operable in the direction of movement of the same for increasing clamping engagement.

A still further object of the invention is to improve portable derails for successful commercial use.

The above recited and other objects of the invention will be apparent from the following description and drawings and will be particularly pointed out in appended claims:

In the drawings:

Figure 1 is a side elevation of the derail of my invention.

Figure 2 is a top plan view of the same.

Figure 3 is an end-elevation looking from the left hand end of Figure 1, and

Figure 4 is the preferred form of target used as a handle for operating the clamp as well as serving as a signal.

In the drawings 5 is a standard T track rail on which the derail of my invention is

adapted to be temporarily mounted. The derail comprises a casting having a substantially flat under surface 6, which rests on the head of the rail and depending side flanges 7 and 8 for maintaining the position of the casting on the rail. The upper surface of the derail casting is provided with a tread 9 for the car wheel which has been displaced, and an upstanding flange 10 defining a groove 11 in which the flange of the wheel is received. In elevation the tread 9 has an upwardly inclined portion 9^a and a flat portion 9^b, the height of which is sufficient to carry the flange of the wheel over the top of the rail. As will be noted in Figure 2 the tread and groove extend diagonally across the casting so as to direct the wheel off of the track, for purposes well understood. The casting has a stirrup integral therewith and depending on one side of the casting as at 12, and having an upturned portion 13. The depending portion 12 is provided with vertically disposed cylindrical recesses 14 and 15 for receiving stub shafts 16 on a cam member 17. The cam member 17 is adapted to be horizontally moved about the vertical axis formed by the stub shaft 16, which cam has a cam surface 18 adapted to be wedged against the web of the rail as is shown in dotted lines in Figure 2 and in full lines in Figure 3. The cam has a bevel segment 19. In the upstanding portion 13 of the stirrup there is mounted for rotative movement in a vertical plane a toothed segment 20, which when in position is in mesh with segment 19 of the cam member 17; member 20 is supported in horizontally disposed journals 21 and 22. Extending upwardly from the member 20 is a handle 23 which in the present instance comprises a tube 24 carrying at its upper end a target 25, on which any desirable legend such as "Stop" may be applied. The handle 23 and the cam 17 are so arranged that when in unlocking position the handle is down, that is, the cam 17 is swung away from contact against the track web and in position to permit application and removal of the derail with respect to the track rail.

In applying the derail to the track rail at any point, the handle 24 is moved downwardly into a substantially horizontal position, whereupon the casting is placed on the ball of the rail and the handle then raised to substantially vertical position. Raising the

handle will by reason of the intermeshing of the members 20 and 17 cause the cam to be swung against the web of the rail and held securely thereagainst. By placing the handle on the inside of the derail any car moving on the track and striking the same would increase the pinch of the cam against the web of the rail, and thus prevent displacement of the derail accidentally. The handle has an outstanding lug 26 provided with an opening 27 therethrough while the casting is provided with a lug 28 having an opening 29 through the same. These lugs 26 and 28 are so arranged that when the handle is in up, that is, in locking position, a chain may be passed through the apertures in these lugs and a padlock applied to lock the derail against removal by an unauthorized person.

20 It will be observed that my invention provides a quick-locking, portable derail which may be quickly applied and removed anywhere along the track rail and which is positively locked in applied position. It is 25 designed to protect the men working under and about cars on line tracks or in repair yards where suitable provision is not made to protect the workmen. It is light; therefore, readily portable and will fit any rail 30 section. It is so made that a car accidentally moved against it would increase the cam action rather than decrease the same, and hence eliminates the possibilities of accidental displacement.

35 While I have described more or less precisely the details of construction of my invention I do not wish to be understood as limiting myself thereto as I contemplate changes in form and proportion of parts 40 and the substitution of equivalents as circumstances may suggest or render expedient without departing from the spirit of my invention.

I claim:

- 45 1. A derail including a casting adapted to rest on a rail head, a cam associated therewith for engaging the rail, said cam adapted to swing about a vertical axis and having a toothed portion, a member carried by said casting and disposed in angular relation to said cam and having a toothed portion for meshing with said cam, and a handle connected to said member for actuating said cam.
- 50 2. A portable derail including a casting having a suitably flanged upper surface and

an under surface adapted to rest on a rail head, a depending yoke, a cam carried in said yoke adapted for contact with the rail web under certain conditions, and another member also carried by said yoke at an angle to said cam for moving the same into and out of engagement with the rail web.

55 3. A portable derail including a casting having a suitably flanged upper surface and an under surface adapted to rest on a rail head, a depending yoke, a cam carried in said yoke adapted for contact with the rail web under certain conditions, and another member also carried by said yoke at an angle to said cam for moving the same into and out of engagement with the rail web, said cam and member having positive non-slip engagement with each other.

60 4. A portable derail including a casting having a suitably flanged upper surface and an under surface adapted to rest on a rail head, a depending yoke, a cam carried in said yoke adapted for contact with the rail web under certain conditions, and another member also carried by said yoke at an angle to said cam for moving the same into and out of engagement with the rail web, said cam and member having toothed engagement with each other.

65 5. A portable derail including a casting adapted to rest on a rail head and having a groove in its upper surface for guiding a wheel, lugs depending from said casting for engaging the sides of the rail head, a yoke depending from said casting, and a wedge carried by said yoke adapted to be moved into wedging engagement with the rail web, a second member carried by said yoke and having non-slip engagement with said wedge, and means for actuating said second member for moving said wedge into and out of wedging engagement with the rail.

70 6. A derail including a casting formed with a wheel flange groove in its upper surface and adapted to rest on a rail head, a yoke depending therefrom, a cam mounted on a vertical axis in said yoke, and adapted to be moved into wedging engagement with the rail web, a lever arm supported on a horizontal axis in said yoke and having toothed engagement with said cam whereby said cam may be moved into and out of wedging contact with the rail web.

75 Signed at Chicago, Illinois, this 23rd day of February, 1922.

RICHARD D. GALLAGHER.
